HANDLE FOR A FILE OR SIMILAR ARTICLE

Ronald G. Cluthe, % Geo. Cluthe Manufacturing Co.
Limited, Waterloo, Ontario, Canada

Filed Feb. 25, 1963, Ser. No. 73,693

Claims priority, application Canada Aug. 23, 1962

Term of patent 14 years

(Cl. D37—1)

FIG. 1

FIG. 3

FIG. 1 is a perspective view of a handle for a file or similar article, showing my new design;

FIG. 2 is a plan view thereof; and

FIG. 3 is a sectional view taken on the plane of line 3—3 of FIG. 1.

The broken line showing of a file in FIG. 1 is for illustrative purposes only.

I claim:

The ornamental design for a handle for a file or similar article, as shown and described.
